GARMENT HANGER

Leonard Louik, 7138 Reynolds St.,
Pittsburgh, Pa. 15208

Filed Nov. 9, 1965, Ser. No. 88,052

Term of patent 14 years

(Cl. D80—8)

I claim:

The ornamental design for a garment hanger, as shown and described.
